UNITED STATES PATENT OFFICE.

WILLIAM FLAGG, OF BROOKLYN, NEW YORK.

STEAM-BOILER.

SPECIFICATION forming part of Letters Patent No. 325,332, dated September 1, 1885.

Application filed June 2, 1885. (No model.)

To all whom it may concern:

Be it known that I, WILLIAM FLAGG, of Brooklyn, in the county of Kings and State of New York, have invented certain new and 5 useful Improvements in Steam - Boilers, of which the following is a specification.

My invention relates to improvements in tubular steam-boilers of the class in which there is kept up a forced circulation of the 10 water being converted into steam; and my object, mainly, is to provide for rapidly generating steam with a minimum amount of fuel.

My invention consists in a novel organization of parts, and in certain combinations of 15 devices, to be particularly pointed out by the claims, after being first described by the aid of the accompanying drawings, which show its application to a marine boiler.

Figure 1 is a front elevation, and Fig. 2 a 20 view, partly in vertical longitudinal central section and partly in side elevation, representing all those parts of the boiler illustration of which is required to convey a proper understanding of a suitable adaptation of my improvements.

The boiler shell or casing A has double ends or heads B C. As shown, the front head, B, is formed of inner and outer plates, *b b'*, and the rear head of inner and outer plates, *c c'*, 30 the plates of the respective heads being suitably bolted together. The water-spaces *a d*, thus provided between the plates of the double heads, extend uninterruptedly from side to side, or entirely across the boiler, and may be 35 divided by separating-partitions into any desired number of smaller spaces of the full width of the boiler to control the course of the water and insure its proper circulation, as soon to be described.

40 A large number of small water-circulating boiler-tubes, D, of, say, an inch or less in diameter, (shown as arranged in parallel rows in a heating - chamber, E,) communicate at their opposite ends with the front and rear water-spaces, and the flames and heated products of combustion pass from the fire-box F, along by 45 way of this boiler-tube heating-chamber E, between and in contact with the boiler-tubes, the waste products of combustion finding outlet by way of the smoke-stack G.

As in this instance shown, the water-space

of the rear head of the boiler is undivided, and the water-space of the opposite head is separated by a partition, *a'*, into upper and lower parts, the lower portion being of less 55 vertical area than the upper, and communicating with the front ends of the three lower-most rows of boiler-tubes. As before stated, the water-spaces (both the front and the rear spaces) may be separated into any desired suitable number of parts by partitions extending across the spaces, and it is not necessary that the relative sizes of the upper and lower portions of the water-space *a* be such as shown.

50 A steam chamber or dome, H, from which the steam passes by an outlet-pipe, *h*, as usual, is connected by means of an inlet-pipe, I, with the boiler. This boiler-connecting pipe I enters the steam-dome at or near its top, and this pipe at its lower end connects with the 70 upper end of the front water-space or head of the boiler. A deflecting plate, *i*, secured at its upper edge to the inner top surface of the steam-dome, projects downwardly a sufficient distance to direct the incoming water toward 75 the bottom of the steam-dome. This deflector terminates at its lower end above the water-level, is inclined, (see Fig. 2,) and serves, as will further on be made apparent, to prevent the water as it enters forcibly into the steam-dome from commingling with the dry steam, which accumulates in the upper part of the steam-dome. The steam entering from the inlet-pipe to the dome finds its way beneath the deflector to the upper part or steam-space 80 of the dome in obvious way.

Near the lower end of the steam-dome a water-circulating pipe, K, communicates with it. The lower end of this return-pipe communicates with a feed-water tank or drum, L. 90 The feed-water is supplied to this drum as needed by a pipe, *l*, in well-known way.

A water-circulating pipe, M, makes communicating connection between the feed-water drum and the boiler. As in this instance 95 shown, this water-circulating pipe M connects at one end with one end of the feed-water drum near its top, and at its opposite end or upright portion, *m*, this pipe communicates with the lower portion of the front water-space, *a*, of the boiler. The upright pipe *m* enters this water-space near the bottom thereof.

A suitable pump, N, operated in appropriate well-known way, serves to keep up a forced circulation of water through the boiler.

From the above description it will be seen that when the pump is in operation water will be forced from the feed-water drum into the front water-space of the boiler, through the lower boiler-tubes to the back water-space, thence through the water-tubes above the partition a' , and by way of the front and back water-spaces and the circulating-pipe I into the steam-dome, to the bottom of which the hot water passes, and thence by way of return water-circulating pipe K back to the feed-water drum, and warming the water therein preparatory to its being forced through the boiler, as the circulation is continuously kept up. It will be seen that as the feed-water is heated and a very large heating-surface provided the steam is rapidly generated with but slight consumption of fuel, the boiler-tubes being of such small diameter that the water within them is very rapidly heated.

In order that the boiler may be kept in operation for short periods, as occasion may require, without using the pump to keep up a forced circulation of the water, an auxiliary communicating-pipe, O, is provided to direct the water from the feed-water drum to the upright portion m of the pipe, which makes communication between the feed-water drum and the boiler-front. The auxiliary communicating-pipe O is provided with valves o P. When the regular operation of the boiler is going on—that is, when the pump is in operation—the valves o P are closed, and when the pump is out of operation and the pipe O in use the valve o is open. Valves q are provided in the communicating-pipe M, and these valves are of course open when the pump is at work. They are closed should the pump get out of order, or when the pump is out of action and the auxiliary communicating-pipe is being employed. The auxiliary communicating-pipe serves as a blow-off pipe, and when so used both of its valves are of course open.

A short pipe, R, provided with a valve, r , connects the pipe I with the lower part of the dome H. Ordinarily the valve r is closed; but when the pump is not in action this valve is opened and facilitates the operation of the boiler when a natural circulation is going on.

Although I have described but one organization of my improvements, I do not wish to be understood as confining my invention in all respects to the details of construction and

arrangement specifically described, as, obviously, my invention may be modified in so such ways as to adapt it for use in connection with boilers differing somewhat from that particularly described herein.

I claim as of my own invention—

1. The combination of the feed-water drum, 65 the front and rear water-spaces of the boiler, the boiler-tubes, means by which the boiler has communicating connection with the feed-water drum, the steam-dome, the water-circulating pipe having inlet communication 70 with it and communicating with the boiler, and the return-water-circulating pipe communicating with the steam-dome and feed-water drum, substantially as and for the purpose set forth. 75

2. The combination of the boiler-tubes, the inner and outer plates constituting the front water-space extending from side to side of the boiler, the partition a' , and the inner and outer plates constituting the rear water-space, 80 likewise extending from side to side of the boiler, substantially as and for the purpose set forth.

3. The combination of the boiler, the steam-dome, the water-circulating pipe by which 85 the water ascends from the boiler to the steam-dome, the return-water-circulating pipe, the feed-water drum communicating with the steam-dome by way of the return-water-circulating pipe, means by which the water is 90 conducted from the feed-water drum to the boiler, and the pump by which a forced circulation of the water through the boiler and water-circulating pipes is kept up, substantially as and for the purpose set forth. 95

4. The combination of the boiler, the steam-dome, its deflector projecting downwardly and terminating above the water-level, and the pipe I, connecting the steam dome and boiler and from which the water issues against 100 the deflector, substantially as and for the purpose set forth.

5. The combination of the feed-water drum, the boiler, the pipe M m , having communication with the boiler and feed-water drum, the 105 pump, the pipe O, the valves of the pipes M and O, the steam-dome, the water-circulating pipe I, and the return-water-circulating pipe, substantially as and for the purpose set forth.

In testimony whereof I have hereunto subscribed my name.

WILLIAM FLAGG.
